UNITED STATES PATENT OFFICE.

SIGMUND FREY, OF LOS ANGELES, CALIFORNIA.

DISCHARGE SPOUT FOR LIQUID CONTAINERS.

Application filed February 28, 1924. Serial No. 695,720.

To all whom it may concern:

Be it known that I, SIGMUND FREY, a citizen of the United States, residing at Los Angeles, in the county of Los Angeles and 5 State of California, have invented a new and useful Discharge Spout for Liquid Containers, of which the following is a specification.

This invention relates to spouts of the 10 character employed on containers for liquid and it is especially serviceable for vessels containing extra supplies of water, gasoline, oil and the like for automobiles.

The invention is also well adapted to be 15 used in connection with liquid measures of the character employed, for example, in measuring desired quantities of oil and discharging said oil into the crank case of an internal combustion engine. The invention 20 is not limited to the uses noted above but is serviceable in connection with any container from which a liquid is to be discharged.

An object of the invention is to provide a 25 discharge spout that can be neatly telescoped within the container when not in use.

Another object of the invention is to provide a spout having a valve that is opened by moving the spout from one position into 30 a different position.

This invention simplifies the construction of spout disclosed in my former Patent No. 1,461,269, dated July 10, 1923 and this simplification is an object that differentiates the 35 present invention from that disclosed in said prior patent.

Other objects and advantages will appear hereinafter.

The accompanying drawings illustrate the 40 invention:

Figure 1 is a side elevation of a container with which the spout embodying the invention is associated, a portion of the container being broken away to show the spout telescoped in closed position within the container.

Fig. 2 is an enlarged elevation of the spout shown in Fig. 1, partly in section and drawn part way out of the container, the valves being closed.

Fig. 3 is a view similar to Fig. 2 showing the parts in position to allow the liquid to flow from the container into the spout.

Figs. 4 and 5 are enlarged plan sections 55 on the lines indicated by 4-4, 5-5, Figs. 2 and 3, respectively.

Fig. 6 is an inverted plan section on the line indicated by 6-6, Fig. 2.

Referring to the form of the invention shown in Figs. 1 to 5, inclusive, there is provided a liquid container 12, shown in Fig. 1 in the form of a canteen provided with a handle 13 and with a cylindrical neck 14 surrounding an opening 15 formed in the top of the canteen. A detachable cap 16 normally 60 closes the neck 14, being, in this instance, screw threaded upon said neck. Secured within the opening 15 is a suitable sleeve valve 20. This sleeve valve may be soldered or otherwise secured in place in a manner 65 to produce a leak-proof joint between it and the canteen. The sleeve valve 20 projects outwardly within the neck 14 and also projects into the interior of the canteen. 70

Slidably fitting the sleeve valve 20 is a 75 discharge tube 18 provided near its inner end with a discharge port or ports 19 which are closed by the sleeve valve 20 when the tube is drawn into the partly extended position shown in Fig. 2. The sleeve valve 20 is provided with a port or ports 21 adapted, when the valve and tube are relatively moved lengthwise to register with the ports 19, as 80 in Fig. 3.

In this particular instance the valve 20 is 85 formed by tubing closed at its lower end by a disc 26.

When decanting liquid from the container, air may be admitted thereto, either by unscrewing the filling cap 30 or through a small 90 orifice 31 in that portion of the wall of the canteen enclosed by the neck 14. This orifice 31 will permit any liquid that may leak from the tube 18 into the neck 14 to drain from the interior of the neck into the canteen. 95 To avoid such leakage, as far as possible, it is preferable to line the cap 16 with a suitable packing 35, for example cork, and the outer end of the tube 18 is expanded at 36 so as to cause said outer end to protrude 100 slightly from the sleeve valve and be engaged by the packing 35.

Within the tube 18 is slidably mounted a slide valve 32 which is yieldingly held in position to close the ports 19 by a coil spring 105 33 that has one end resting against the inside of the upper end of the valve 32 and its other end against the disc 27. In order to hold the valve 32 stationary when the tube 18 is pulled upwardly beyond a pre-determined point, the upper end of the valve 32 is connected by suitable means, such as 110

a cotter pin 34, to the disc 26, said cotter pin extending through the disc 27 and having its ends bent outwardly over the outer surface of the disc 26.

5 The cotter pin 34 is sufficiently long to permit the valve 32 to close the ports 19 and, when the tube 18 is drawn into position to register the ports 19, 21, the disc 27 is pulled toward the valve 32 against 10 the pressure of the spring 33. Thus the spring 33 functions to yieldingly hold the tube 18 toward the disc 26 to close the ports 21. The disc 26 is loosely seated against the inner end of the sleeve valve 20 so that, 15 when the tube 18 is pushed inwardly from the position shown in Fig. 2, said disc 26 will leave the sleeve valve 20 and travel inwardly with the tube 18.

To use the invention, when it is desired 20 to decant liquid from the container 12, the cap 16 will be removed and the tube 18 withdrawn from the canteen until the disc 26 strikes the sleeve valve 20, as in Fig. 2. The discharge end of the tube 18 will then 25 be inserted in the opening of the vessel that is to receive the liquid and, the tube 18 will be further extended against the pressure of the spring 33 to cause the ports 19, 30 21 to register, in which position of the tube 35 the valve 32 uncovers the ports 19, as in Fig. 3. To facilitate use of the nozzle, it is preferable to provide a shoulder 37 near the outer end of the tube 18, which shoulder is engaged in the opening of the vessel that 40 is being filled, and the container 12 is pulled away from said vessel, thus effecting extension of the tube 18 and consequent opening of the ports 19 and 21.

I claim:

40 1. The combination with a liquid container of a sleeve valve in the wall of the container provided with a port, a tube slidably mounted in the sleeve valve and provided with a port and closed at its inner end, and valve means in the tube operable by the sleeve valve to uncover said second port when the tube is slid through the sleeve valve.

45 2. The combination with a liquid container, of a sleeve valve in the wall of the container provided with a port, a tube

slidable in the sleeve valve and provided with a port and closed at its inner end, a valve for controlling the port in the tube, a spring tending to keep the ports out of register and means connected with the second valve and engageable by the inner end of the sleeve valve to hold the second valve in fixed position when the tube is extended to bring the ports into register.

55 3. A discharge spout comprising a sleeve having a port, means to connect the sleeve with a liquid container, a tube slidably mounted in the sleeve and provided with a port adapted to register with the first port when the tube is in one position, a slide valve inside of the tube, a spring tending to hold the slide valve in position to close the second port, and means engageable by the sleeve when the tube is moved from a second position into the first mentioned position to hold the slide valve stationary relative to the tube.

60 4. A discharge spout comprising a sleeve having a port, means to connect the sleeve with a liquid container, a tube slidably mounted in the sleeve and provided with a port adapted to register with the first port when the tube is in one position, a slide valve inside of the tube, a spring tending to hold the slide valve in position to close the second port, and means operating when the tube is moved from a second position into the first mentioned position to hold the slide valve stationary relative to the tube.

65 5. A discharge spout comprising a sleeve having a port, means to connect the sleeve with a liquid container, a tube slidably mounted in the sleeve and provided with a port adapted to register with the first port when the tube is in one position, a slide valve inside of the tube, a disk closing the inner end of the tube, a pin extending through the disk and connected at one end with the slide valve, a second disk on the pin engageable with one end of the sleeve, and a spring between the first mentioned disk and one end of the slide valve.

70 75 80 85 90 95 Signed at Los Angeles, California, this 23rd day of February, 1924.

SIGMUND FREY.
